ELECTRIC HEATING ELEMENT

John A. Knight, Hamilton, Ontario, Canada

Application April 27, 1934, Serial No. 722,694

9 Claims. (Cl. 219—38)

This invention relates to electric heating elements of the resistance type which are exteriorly applied to the outer surfaces of cylindrical tanks or conduits to heat a fluid contained therein or flowing therethrough, and one object of my invention is to produce an element of this type which will present a path of very high heat conductivity between the resistance element and the exterior surface of the tank. A further object of my invention is to produce a heating element, which, though not flexible in the strict meaning of the term, is readily adaptable to several diameters of tank within a limited range. A further object is to provide a durable path of low resistance between the resistance element and the connecting terminals and to provide a satisfactory supporting connection between the heating element and the terminals. A further object is to provide a terminal chamber where the connection to the source of power is made having a comparatively low temperature therein so that the insulation on the wires leading to the heater may not be damaged and a good electrical connection will be maintained. A further object is to provide a convenient and practical arrangement for assembling the parts together.

I attain these objects by means of the constructions hereinafter described and illustrated in the accompanying drawing in which

- Fig. 1 is a plan view of the heating element;
 Fig. 2 an inside elevation on an enlarged scale and partly broken away of part of the same;
 Fig. 3 a longitudinal section on the line 3—3 in Fig. 2;
 Fig. 4 a front elevation partly broken away and partly in section of part of the same; and
 Fig. 5 a detail illustrating the connection between the resistance element ribbon and the leads therefor.
- In the drawing like numerals of reference indicate corresponding parts in the different figures. Referring to the drawing, 8 is a very thin metal facing band formed of a metal of high heat conductivity and sufficiently soft or malleable to readily conform to the surface to which it is applied. Sheet aluminum about .015" thick is satisfactory. Behind this is positioned the resistance element comprising resistance wire 5 wound on a mica or other insulating band 4. A thin flat ribbon is used as it presents a large conducting surface towards the facing band and thus transfers heat more effectively. A thin band 7 of insulation, preferably mica of a thickness of about .010" is positioned in front of the resistance element and provides a path of high heat

conductivity between the resistance ribbon and the facing band.

Behind the resistance element is positioned an insulating band 3, preferably of mica.

Behind the band 3 is positioned the cushioning band 2 which is preferably of heat insulating material and is sufficiently soft to be readily compressible, as its function is to convey a resilient pressure from a supporting band 1 to the underlying parts to hold them in close contact with the facing band 8 in close contact with all parts of the surface of a cylindrical tank or conduit to which the device is applied.

The supporting band is semi-rigid. That is to say that it is stiff enough to apply pressure as described but flexible enough to permit its diameter to be varied through a limited range to fit different diameters of tank.

To retain the parts in assembled relationship, I form the facing band 8 of a greater width than the other bands which are approximately of the same width and fold its edges over the edges of the other bands into engagement with the back of the supporting band.

The preferred method of assembly is to bend the metal strip 8 into the form of a straight channel, roll the channel to ring form, assemble the other bands within the channel, and finally roll in the sides of the channel over the edges of the other bands as described.

The completed structure has its ends in juxtaposition and is clamped about a tank by means of a bolt passing through lugs 14 formed on the ends of the band 1. It is found that a structure such as described presents such a high heat-conductive path between the resistance and the wall of the tank that substantially the highest possible efficiency is attained.

The second feature of my invention lies in the means for forming a connection between the resistance ribbon and the source of current supply. For this purpose I employ a metal connection box 12 in the bottom of which is formed a hole 18.

In the supporting band 1 is formed a hole 19. A plate 17 is welded to the band 1 and has a hole 18 therein alined with the hole 19. The connection box 12 is secured to the plate 17 in spaced relationship, preferably by the following means. A block 11 of insulating material carries the terminals 10, and is spaced from the bottom of the box 12 by the lugs 20. Between the bottom of the box and the block 11 are positioned the block or blocks 15 of insulating material. Through the block 11, the lugs 20, the bottom of

the box 12, and the blocks 15 pass the screws 21, which are threaded into the plate 17 and hold the parts together.

A weak point in heaters of this type, both mechanically and electrically, is the connection between the resistance ribbon or wire and the terminals. It is desirable that such connections should be mechanically strong and electrically of low resistance to avoid transfer of heat to the terminals. I form these connections in the following manner. For the leads from the terminals I employ pieces 6 of metal ribbon having a much lower resistance per unit of length than the ribbon 5. Preferably the pieces of ribbon 6 are of the same width as the ribbon 5, but thicker. The ribbon 6 is positioned beneath the ribbon 5 at its last bend over the insulating band 4 before being brought out through the openings in the insulation band 3 and the cushioning band 2. The superimposed ribbons are then coiled around a mandrel, the mandrel withdrawn and the bands flattened together, this coiling and flattening taking place adjacent to the last fold over the edge of the insulating band 4. The coiling of the bands around a mandrel and then flattening them together causes them to be forced into high pressure contact each with the other, giving a mechanically strong connection and one of low electrical resistance. The superimposed parts are then brought out through openings in the insulation and cushioning band to the terminals. Very little heat therefore is generated in the connections which not only is conducive to durability, but also to efficiency, which is further aided by the arrangement of the connection box in spaced and insulated relationship to the supporting band.

What I claim as my invention is:

1. An electrical heating element comprising a thin metal facing band; an insulated resistance element applied to the outer surface of the facing band; a cushion band applied outside the resistance element; a semi-rigid supporting band of metal formed as a split ring; and means for drawing its ends together to clamp it about a cylindrical surface and thus press the cushion against the insulated resistance element; the resistance element against the facing band and the latter against the surface to which the heating element is applied.
2. An electrical heating element comprising a thin metal facing band; an insulated resistance element applied to the outer surface of the facing band and including a thin broad metal ribbon laid flatwise relative to the facing band; a cushion band applied outside the resistance element; a semi-rigid supporting band of metal formed as a split ring; and means for drawing its ends together to clamp it about a cylindrical

surface and thus press the cushion against the insulated resistance element, the resistance element against the facing band and the latter against the surface to which the heating element is applied.

3. An electric heating element according to claim 1 in which the edges of the metal facing band are formed over the edges of the supporting band to enclose the resistance element and cushion.

4. An electrical heating element of band form having an external metal supporting band; a metal plate tangential to the band and welded thereto; and a terminal box secured to the said plate and in spaced relation thereto.

5. An electrical heating element of band form having an external metal supporting band; a metal plate tangential to the band and welded thereto; a terminal box secured to the said plate; a block or blocks of heat insulating material secured in the box from the plate; and fastening means engaging the box and plate and extending through the block.

6. An electrical heating element of band form having an external metal supporting band formed with a hole for the passage of leads for the element; a metal plate also having a hole therein registering with the hole in the band and welded to the band about the hole; and a terminal box secured to the said plate in spaced relation thereto and also having a hole aligned with the holes aforesaid.

7. An electrical resistance element comprising a metallic ribbon of high electric resistance wound on an insulating support; and leads formed of a metallic ribbon of lower resistance per unit of length than the first mentioned ribbon, the ends of the latter being juxtaposed in flat folds.

8. An electrical heating element of band form having an external metal supporting band; a terminal box secured to said band; terminals carried by the box; and washers of heat insulating material spacing the box from the band and coincident openings in the band, the insulating washers and the box through which connection may be made from a resistance element to the terminals in the box.

9. An electrical resistance element comprising a metallic ribbon of high electrical resistance wound on an insulating support; and leads formed of a metallic ribbon of lower resistance per unit of length than the first mentioned ribbon, the two ribbons being juxtaposed each on the other in a series of short flat contiguous folds forming a high pressure connection of low electrical resistance.

JOHN A. KNIGHT.
